UNITED STATES PATENT OFFICE.

JACOB A. JOHNTRY, OF BROOKLYN, NEW YORK, ASSIGNOR OF ONE-HALF
TO ISAAC SMITH REMSON, OF SAME PLACE.

SHOVEL.

SPECIFICATION forming part of Letters Patent No. 256,325, dated April 11, 1882.

Application filed February 25, 1882. (No model.)

To all whom it may concern:

Be it known that I, JACOB A. JOHNTRY, of Brooklyn, in the State of New York, a citizen of the United States, have invented a new and 5 useful Improvement in Shovels, of which the following is a specification.

The nature of my invention consists in the application of a strip of hard india-rubber at the end of a shovel, whereby articles such as 10 sinks, &c., can be scraped and cleaned and then taken up by the shovel, saving thereby the use of a brush for that purpose.

In the accompanying drawings, Figure I represents the stamped-out shovel before the india-rubber is attached to the same. Fig. II is 15 a top view of a shovel with the india-rubber attached. Fig. III is an end view of the same.

Similar letters represent similar parts.

A represents the shovel, made in any de- 20 sired shape. To the forward end a strip of india-rubber, B, is attached, projecting about one-sixteenth of an inch or more. This india-rubber strip may be fastened to the end by placing the same underneath the end edge, and 25 then putting a thin piece of metal at the outside and riveting the same to the shovel.

To simplify the attachment, make the same with less trouble and expense, and at the same time make the end of the shovel as smooth as

possible, I form the blank of the shovel with 30 projecting strips *m m* at the sides at the end, Fig. I, which, after the india-rubber is placed at the back of the shovel, are bent around the india-rubber, and the ends of said strips *m m* are then passed through the india-rubber strip 35 B and the body of the shovel A, and then hammered down flat.

By this improved shovel, sinks and similar articles, particularly when the same are wet, can easily be scraped and cleaned, better than 40 by the use of a brush, by holding the shovel edgewise to the surface, and then the thus collected dirt shoveled up.

What I claim as my invention, and desire to secure by Letters Patent, is—

1. In combination with the edge of a shovel, a strip of india-rubber, B, projecting a short 45 distance over the edge of the shovel, substantially in the manner and for the purpose described.

2. A shovel-blank provided with projecting strips *m m* at the sides at its end, substantially 50 for the purpose specified.

JACOB A. JOHNTRY.
